UNITED STATES PATENT OFFICE.

JARVIS A. DAUGHERTY, OF ST. LOUIS, MISSOURI.

FENCE-POST.

SPECIFICATION forming part of Letters Patent No. 415,266, dated November 19, 1889.

Application filed May 13, 1889. Serial No. 310,588. (No model.)

To all whom it may concern:

Be it known that I, JARVIS A. DAUGHERTY, a citizen of the United States, residing at the city of St. Louis, State of Missouri, have invented certain new and useful Improvements 5 in Fence or other Posts, of which the following is a full, clear, and exact description.

My invention relates to improvements in fence, lamp, or other posts, and has for its 10 object to insure a firm anchorage thereto and to enable a series of panels of wire fencing, stretched and gaged for use, to be easily transported and adjusted to the posts wherever the latter may have been previously fixed.

15 It consists in a post having a detachable bar or portion, combined with other features of novelty, as hereinafter claimed.

On the accompanying drawings, Figure 1 represents a front elevation of two of my 20 improved posts as applied to a wire fence, (one post partly in section;) Fig. 2, a side view of one of the posts (partly broken away) at right angles to Fig. 1; Figs. 3, 4, 5, and 6, transverse sections thereof, to an enlarged scale, on 25 lines 1 1, 2 2, 3 3, and 4 4, respectively, in Fig. 1; Fig. 7, a modification of my invention as applied to an ornamental paling, lamp, or other post; and Fig. 8, a plan thereof, to an enlarged scale, omitting the superstructure.

30 Like letters of reference denote like parts in the respective figures.

a represents a fence-post which for its entire height from the base-piece b is preferably of a semi-diamond or square shape with 35 flattened corners in cross-section, but may be made semicircular, oval, rectangular, or otherwise, as desired.

The post a is preferably made in one piece with the base b, which projects beyond the 40 post a on one side, so as to form a shoulder b' at the foot of the post a, as seen more particularly in Fig. 2. From the base b depends the shank c, around which is formed or secured a screw-blade (or thread) d, whereby, 45 on turning the post a, the base b, with its shank c, is caused to enter the ground, and when at the proper level there is placed around the base b, preferably, a sleeve e, from which project horizontally and at right angles (or 50 inclined) to each other four (more or less) ribs

or wings f, the sleeve e being secured to the base b by screws e' or otherwise, so that on dumping the ground around the sleeve e and between the wings f the post a is prevented from lateral play and firmly anchored in position. 55

Against each post a for its entire height on that side overlying the shoulder b' of the base b is fitted, with its lower end butting upon the shoulder b', a detachable bar g, to a series of 60 which, when separate from the posts a, the wires h of the fence, previously stretched, are gaged and loosely held by staples i or other device for facility of transportation, so that, on the bars g being adjusted to the distances 65 between the posts a and fixed to the latter by bolts j, the wires h are finally secured to the bars g by driving home the staples i, thereby forming a continuous wire fence without unnecessary breaks, which can be readily 70 and quickly fixed.

In the case of a board fence the ends of the boards may be nailed either with lap or butt joints to the respective bars g of the posts a, so that any portion of the fence can be removed by detaching the bars g without disturbing the posts a. 75

In the modification of my invention seen in Figs. 7 and 8 the fixed part a' is shortened to within a suitable distance from the base 80 b' and the detachable portion or ornamental post a'' secured to the fixed part a' with its lower end bearing upon the upper collar or shoulder b'' of the base b', and upon the upper edges of the webs or wings f', which in 85 this case are shown dovetailed into the base b' without the sleeve e shown in Figs. 1, 2, and 5, although the latter arrangement may be used if preferred.

I claim— 90

1. The combination, in a fence-post, of a section having a ground point and a shoulder, a detachable section adapted to rest on the shoulder of the ground-point section, and a base-collar adapted to slip over the post above 95 the point, substantially as and for the purposes described.

2. The combination, with a fence-post section having a screw-point and a shoulder or offset above the same, of a detachable post-section 100

and a collar-base adapted to fit on the post-sections above the screw-point, substantially as and for the purposes described.

3. In a fence-post, the combination of a base-piece having a screwed shank and a shoulder on one side of the post, a sleeve adapted to the base-piece, and having webs or wings, with a detachable bar, substantially as shown and for the purpose described.

In testimony whereof I affix my signature, to
in presence of two witnesses, this 13th day of
April, 1889.

JARVIS A. DAUGHERTY.

Witnesses:

S. L. SCHRADER,
PAUL BAKEWELL.
